UNITED STATES PATENT OFFICE.

EDWARD PIERCE, OF WEST BURLINGTON, IOWA.

LOCOMOTIVE-STOKER.

1,277,641.

Specification of Letters Patent. Patented Sept. 3, 1918.

Application filed August 13, 1914. Serial No. 856,630.

To all whom it may concern:

Be it known that I, EDWARD PIERCE, a citizen of the United States, residing at West Burlington, in the county of Des Moines and State of Iowa, have invented certain new and useful Improvements in Locomotive-Stokers, of which the following is a specification.

This invention relates to improvements in locomotive stokers, and has for its object to provide a new and improved device of that class with which coal or other solid fuel may be automatically taken from the tender or other coal supply and distributed in and throughout the fire box of the locomotive.

The main object of my device is to provide such a stoker by which all the necessary operations may be performed mechanically, if so desired. At the same time I provide for emergencies or unusual or variable conditions by providing manually operating means to enable concentration of the coal supply in any one portion of the fire box, this means being also operable to permit manual operation of the distributing means which insures distribution of the coal throughout the fire box.

Still another object of my invention is to provide a new and improved form of coal-conveying means coacting with the distributing means and operating to take coal from the tender or other coal supply and deliver it during the operation of the device to the distributing means.

Still another object is to provide mechanism of the class described which will not interfere with the firing of the locomotive by hand.

Still another object is to provide specific construction and mechanism to enable me to carry out these objects, and I have more fully set forth and described such mechanism in the following specification and shown it in the accompanying drawings, in which—

Figure 1 is a side elevation of a portion of a locomotive and tender with my invention applied thereto, a portion of the fire box being shown in section.

Fig. 2 is a front elevation of my invention applied to a locomotive, a portion being shown in section.

Fig. 3 is a plan view of a portion of the interior of the locomotive fire box showing my invention with its relation thereto.

Fig. 4 is a vertical section of the closure

and nozzle member together with a portion of the operating mechanism of the latter.

Fig. 5 is a horizontal section of the nozzle, showing the detachable tip thereof. 60

Fig. 6 is a vertical transverse section taken along the line 6—6 of Fig. 4.

Fig. 7 is a horizontal section of the closure and nozzle taken along the line 7—7 of Fig. 4. 65

Fig. 8 is a side elevation of a portion of the conveyer.

Fig. 9 is a plan view of the same.

Fig. 10 is a perspective of the door or closure hinge. 70

Fig. 11 is a side elevation of one of the operating levers and associated mechanism; and

Fig. 12 is a side elevation of a starting and operating lever. 75

Like numerals refer to like elements throughout the drawings, in which 15 designates generally a locomotive having a fire box 15^a with the end wall 15^b, in which is the usual opening 15^c. I have further shown, coupled to and associated with this locomotive, the usual form of tender 16, in which is carried a supply of coal, or the like, 80 17.

I provide a conveyer member, generally 85 indicated by numeral 18 and comprising a tube 18^a, in which is rotatably mounted a helical screw 18^b secured to the shaft 18^c. This tube 18^a is open at one end and the screw 18^b and shaft 18^c project therebeyond, 90

as clearly shown in Fig. 1. At the other end of the tube 18 is secured the discharge casing 18^d having the outlet 18^e. This casing is pivotally mounted at 18^f to a bracket 16^a carried by the upright 16^b, in turn secured to and carried by the tender 16. This pivotal mounting 18^f in the conveyer 18 permits the same to rotate freely, and it may be placed with its open end upon the top of the coal supply 17 after the same has been loaded 95

into the tender 16, or it may be permitted to drop to the position indicated in dotted lines in Fig. 1, previous to the loading of the coal. In either event the operation is similar, since proper rotation of the shaft 18^c will cause the 100 conveyer screw 18^b to transport the coal, or like fuel, to the discharge casing 18^d in a well-known manner.

A second conveyer, generally indicated by numeral 19, is located in the engine or locomotive cab in the form shown, comprising the horizontally extending tube 19^a, in which 110

is mounted the helical screw 19^b carried on the shaft 19^c. A hopper or receiving casing 19^d is carried by and communicates with the tube 19^a, and is so arranged relative to discharge casing 18^a of conveyer 18 that no matter in what position the latter rests the coal discharged from casing 18^a will fall into hopper 19^d, as will be apparent. The shaft 19^c is operatively connected to shaft 18^c by 10 means of the flexible shaft 20 of a well-known construction.

Coacting with the conveyer sleeve 19^a is the vertical tube or conduit 21 provided with the angularly disposed elbow 21^a, in 15 which is inserted the conveyer tube 19^a. The shaft 19^c extends through and is journaled in the elbow 21^a, and carries the bevel gear 21^b at its outer extremity, as shown in Fig. 1. The tube 21 is supported by the looped 20 brackets 21^c, 21^d carried by the locomotive structure, and it terminates in the open end 21^e. Located adjacent and in normal alignment with this open end is the open end of the short tube 22^a, formed integral with the 25 closure casing 22, as I term it, see Fig. 4. This closure 22 is provided with the passage 22^b therethrough, the same being directed at an angle to the aperture in the tube portion 22^a, as is clearly shown in Fig. 4. This 30 closure is further provided with the enlarged cavity 22^c therein, in which is mounted what I term a distributing nozzle 23, comprising the main portion 23^a and tip 23^b. The latter is inclined downwardly a 35 slight amount, and is formed with the grooved shoulders 23^d fitting over and engaging the flanges or shoulders 23^e of the main portion 23^a of the nozzle 23. This construction is such that the tip 23^b may be 40 readily removed from the main portion 23^a and a new one placed thereon at a minimum of trouble. I find this construction advantageous, since this tip projects into the fire box of the locomotive, and is consequently 45 subjected to intense heat, and in time will burn off, requiring replacement. A small apron, or shield 23^f projects upwardly from the top 23^b for a purpose to be hereinafter described. On its upper surface the main 50 portion 23^a of nozzle 23 is provided with the upwardly extending shoulders 23^g between which extends, and to which is secured, the strip 23^h. An arm 24 is provided in the upper portion of the cavity 22^c, this arm 55 being provided with an elongated slot 24^a fitting around and engaging the strip 23^h, as clearly shown in Figs. 4 and 6. Adjacent one extremity this arm 24 is secured to the shaft 25. On its lower surface the nozzle 60 portion 23^a is provided with the spaced apart lugs 23ⁱ apertured as indicated at 23^j, see Fig. 6. Between these lugs is located the head 26^a formed on a stub shaft 26. This head is held between the shoulders 23^k 65 by the pin 26^b permitting vertical movement

of the nozzle 23^a relative to the head 26^a. Intermediate of the head 26^a and main portion of the stub shaft 26 is formed the collar or flange 26^c normally resting on the interior face of cavity 22^c, in closure 22. The 70 stub shaft 26 projects through an aperture in the wall of this cavity as is clearly shown in Fig. 4. An auxiliary door 22^m is hingedly mounted on the closure and controls the opening 22ⁿ communicating with the aperture 22^b in the closure 22. This opening enables the fireman to glance through into the fire box to observe the condition of his fire without swinging the main closure 22 to open position. Furthermore, should it be 75 desirable to add additional coal, the same may be inserted through the opening 22ⁿ and be distributed by the nozzle 23. The arms 22°, 22^p are formed integral with the closure 22 and project to one side thereof to permit 80 the hinging of the same, see Figs. 2 and 3. These arms have the angularly disposed extremities 22°, 22^p respectively, see Figs. 3 and 7. Adjacent their extremities these arms 22°, 22^p are apertured. Through these 85 apertures extends the hinge rod 27 centrally apertured at 27^a. The arms 22^o, 22^p are secured to this hinge rod by means of set screws 28 or the like. This hinge rod, as I term it, is shown in perspective in Fig. 10, 90 and as stated above, is centrally apertured at 27^a. Cross or transverse grooves 27^b, 27^c are provided near the top and bottom thereof, the same not intersecting the aperture 27^a. Small apertures or bores 27^d extend 95 between these grooves 27^b, 27^c, as shown in Fig. 10. A cross aperture 27^e is provided in the rod 27 near the bottom thereof, the same communicating with the aperture 27^a between a pair of the apertures 27^d without 100 intersecting with any of the latter. Supporting lugs or flanges 29 project outwardly 105 from the base of the locomotive structure, as shown in Fig. 2. These lugs are suitably apertured to provide bearings for the hinge 110 rod or sleeve 27 and the latter is passed through the said apertures and also through the apertures in the arms 22°, 22^p. When the structure is assembled the apertured extremities of the said arms lie adjacent to 115 and upon the lugs 29, the latter, together with the hinge rod 27, forming a pivotal mounting for the door closure 22, as will be apparent. The arm 22^p is provided with the aperture 22^r therein, leading from aperture 27^b, in rod 27, as clearly shown in dotted lines in Fig. 7. This bore or aperture 22^r 120 communicates with a plurality of passages 22^s in the closure 22, these latter discharging from the aperture 22^r into the passage 22^b 125 and from thence into and through the nozzle 23 approximately axially therewith for a purpose to be described later. Carried by the closure 22 are a plurality of glands 22^t providing a threaded mounting for valves 22^u 130

which coact with passages 22^a to control flow of fluid therethrough, as will be more fully described. Similarly the arm 22^a is provided with a passage 22^b, see Fig 2, which 5 communicates with the cross groove 27^a in hinge rod 27 and leads to a plurality of passages 22^c, see Fig. 4, in the closure 22, these latter discharging into the passage 22^b adjacent the bend thereof. It will be apparent 10 that these passages 22^c through the medium of passage 22^b, are in communication with the small apertures 27^a of rod 27. A casing 30 extends across the top of the end of the locomotive structure and is secured thereto or 15 formed therewith, this casing being formed with an elbow or angularly disposed portion 30^a. In this elbow portion 30^a is provided the chamber 30^b with which communicates an aperture 27^a of the rod 27, shown in Fig. 20 2. Since the latter must rotate relative to this casing 30, I provide a stuffing-box or gland 30^c threaded into the elbow 30^a, the same being centrally apertured at 30^d to permit communication of aperture 27^a of rod 27 25 with the chamber 30^b. This gland 30^c is provided with the internal shoulder 30^e against which may abut the end of the rod 27 to prevent longitudinal movement thereof. Below the gland 30^c in the elbow 30^a 30 is provided a small chamber 30^f in which is located the cross groove 27^c of rod 27. At the lower extremity of the elbow 30^a and threaded thereinto is the gland 30^g which is constructed to permit insertion 35 therethrough of the rod 27 and preventing leakage of gas or fluid from chamber 30^f. Similarly a gland 27^g is threaded into the lower end of the rod 27 to prevent leakage therefrom, as will be more fully explained 40 below. Mounted upon the locomotive structure adjacent the top thereof is the engine or prime mover 40 comprising, in the form shown, a two cylinder steam engine of conventional type, provided with the reciprocating pistons 40^a, 40^b arranged through intermediate mechanism, well known, to operate the crank shaft 40^c, the same projecting outwardly of the engine at one side and carrying attached thereto ratchet wheel 41, 45 see Figs. 1, 2 and 12. At the other side of the engine 40 the shaft 40^c extends across the front of the fire box structure and is mounted and journaled in the casing 30, as is clearly shown in Fig. 2. Intermediate its extremities this shaft 40^c is provided with the worm 40^d meshing with a worm gear 42^a on upright shaft 42. At its extremity the shaft 40^c is provided with the bevel gear 40^e meshing with a second bevel gear 43^a carried 50 upon upright shaft 43 which extends down through the aperture 30^d in gland 30^c and through the central aperture 27^a and hinge rod 27, this shaft 43 being of less diameter than that of the said aperture. Adjacent 55 its lower extremity this shaft 43 projects through the gland 27^g and carries a second bevel gear 43^b which meshes with a bevel gear 45^a carried by a cross shaft 45. This shaft is journaled in the bearing 46^a carried by bracket 46 depending from the door 70 closure 22, see Fig. 2, and extends through an apertured boss 47^a in one side of the U-shaped bracket 47 also depending from the door closure 22. Inwardly of the boss 47^a which also serves to journal this shaft 75 45, the latter is provided with a bevel gear 45^b. This bevel gear 45^b meshes with another bevel gear 48^a secured to a short shaft 48 which is journaled in the upright bearing 47^b carried by U-bracket 47. 80 The collar 48^b is secured to the shaft 48 below the bracket 47 to prevent displacement of the shaft 48. Carried by the bevel gear 48^a is the block 49 slotted at 49^a, upright flanges 49^b being arranged at each 85 end of the slot 49^a. Journaled in these flanges 49^b is the threaded rod 50 projecting outwardly of the block 49 and provided with the operating or engaging head 50^a, see Fig. 4. A small block 51 is slidably mounted in 90 the slot 49, being internally apertured and threaded for engagement by the threaded rod 50 and being further provided with the upwardly extending stud 51^a. A second block 52 is secured by a pin 52^a to the stub 95 shaft 26 and this block 52 is provided with the slot 52^b in which is slidably mounted the stud 51^a. The eccentricity of this stud 51^a relative to the rotatable shaft 48 may be varied by operation of the rod 50, as will be 100 apparent. It will be also apparent that when this stud 51^a is eccentrically located with respect to the shaft 48, rotation of the latter will result in oscillation of the shaft 26 and thereby cause horizontal oscillation or movement of the nozzle 23. The amount of this oscillation may be varied by varying the eccentricity of the stud 51^a relative to the shaft 48. The bevel gear 48^a also meshes 105 with bevel gear 55 provided with a hub or sleeve 55^a mounted upon and secured to shaft 56 which extends through and is journaled in the boss 47^c and carried by one arm of the U bracket 47. This shaft 56 is secured to the block 57 at one extremity, this block 110 being similar to block 49 and being provided with slot 57^a terminating at the flanges 57^b, 57^c in which is journaled threaded rod 58 having a head 58^a. A small block 59 is slidably mounted in the slot 57^a and is centrally apertured and threaded for engagement by rod 58. This block 59 is provided with the outwardly extending stud 59^a. A lever 60 depends adjacent the block 57 and is provided with an elongated slot 60^a therein, in which fits the stud 59^a. This lever adjacent its upper extremity is rotatably mounted upon the hub 61^a of a second lever 61 which in turn is secured to shaft 25 adjacent one extremity thereof. A bracket 115 120 125 130

22^x extends upwardly from the closure 22 and is provided with a notched quadrant 22^z, see Figs. 1, 2 and 11. This lever 61 is provided with the handle portion 61^b and 5 carries pivoted to it at 61^c the elbow 61^d of clutch arm 61^e. The link 61^f is pivoted at one extremity to the elbow 61^d and at its other to projecting arm 61^g of a block 61^h slidably mounted on the lever 61. This 10 block 61^h is provided with the outwardly extending spur or tooth 61ⁱ; see Fig. 2, for example, adapted to engage the notched quadrant 22^z when properly operated. A leaf spring 61^k is located between the clutch 15 arm 61^e and handle 61^b, the arrangement of this mechanism being further described below. At its upper portion the lever 60 is provided with the radially arranged raised teeth 60^e, see Fig. 11, forming notches there- 20 between in which is adapted to fit a tooth 61^m in the lower portion of block 61^h.

It will be apparent that when the stud 59^a is eccentrically mounted with respect to shaft 56, rotation of the latter will result in 25 the oscillation of the lever 60 about its upper extremity. When the block 61^h is in the position shown in Fig. 11, lever 61 will rotate with lever 60 through the medium of engagement of tooth 61^m with teeth 60^e, so 30 that the oscillation of the lever 60 will result in oscillation of the shaft 25 and a consequent vertical oscillation of the arm 24—see Fig. 4. This will result in vertical oscillation of the nozzle 23 about the pin 26^b 35 as an axis, this oscillation being permitted by means of the slot 24^a in arm 24. When the clutch handle 61^e is brought to position adjacent handle 61^b, block 61^h will be raised to position in which the spur 61ⁱ will engage 40 one of the notches in the quadrant 22^z; and I preferably construct this mechanism so that this position will be retained until the clutch handle 61^e is positively moved from handle 61^b. When the tooth 61^m is out of 45 engagement with teeth 60^e, lever 60 may oscillate on the hub 61^a and no oscillation will be imparted to shaft 25. When it is desired to manually oscillate shaft 25 and thereby move said nozzle 23 up and down, 50 the tooth 61^m may be lifted out of engagement with teeth 60^e and lever 61 may be manually operated, as desired. If it is desired to maintain nozzle 23 in desired position in its path of vertical travel it may be 55 moved there by manual operation of lever 61 and the spur 61ⁱ may then be moved into engagement with quadrant 22^z to retain the nozzle in such position. It will be obvious that I may vary this amount of oscillation 60 from zero to a maximum by proper positioning of the block 59 through the medium of threaded rod 58. Shaft 42,—see Fig. 2—rotated by shaft 40^e carries a bevel gear 42^b at its upper end, this gear being in mesh 65 with bevel gear 21^b, and it will be seen that

the shaft 40^e will operate to actuate the conveyer shaft 19^e, which, in turn, through the medium of flexible shaft 20, will operate the second conveyer shaft 18^e.

A lever 70 is provided, having a bifurcated portion providing arms 70^a—see Fig. 2—located one on each side of the ratchet wheel 41, and rotatably mounted on shaft 40^e. A pawl 70^b is pivotally mounted between the arms 70^a on pin 70^c,—see Fig. 12— 75 and is adapted to engage teeth in the ratchet 41 when in proper position and properly moved, as will be apparent. The lever 70 is further provided with the handle portion 70^d at its upper portion, and a clutch handle 80 70^e is provided, this being pivotally attached at 70^f to the lever 70. A link 70^g is pivotally attached at one extremity to the pawl 70^b, and at the other to the clutch handle 70^e. When the latter is in the position 85 shown in Fig. 12, the lever 70 may be oscillated in one direction to permit the pawl 70^b to slip over the teeth of the ratchet 41, and when reverse motion is imparted to it, the pawl 70^b will engage a tooth of ratchet 41, 90 operating to rotate the same and thereby the shaft 40^e.

When the handle 70^e is brought to position adjacent the handle 70^d against the action of a leaf spring 70^h placed therebetween, pawl 70^b will be brought out of engagement with ratchet 41. To provide means for maintaining the pawl in this position, I provide a bracket 70ⁱ,—see Figs. 2 and 12—this bracket being provided with a notch 70^j, in which is 100 adapted to fit a depending spur 70^m carried by the clutch handle 70^e. The latter may be moved adjacent the handle and the spur allowed to rest in the notch 70^k, in which position pawl 70^b will not contact with 105 ratchet 41.

A small steam chamber 80 is provided,—see Fig. 2—to which leads a steam supply pipe 81, of any suitable source of steam or the like, such as the locomotive boiler. A 110 valve 80^a is rotatably mounted in the chamber 80, and a stem 80^b projects upwardly therefrom out of said chamber, and an operating handle 80^c is attached to the extremity thereof. A steam pipe 80^d leads from below said valve 80^a to said engine 40, and a second steam pipe 80^e also leads from beneath said valve 80^a to the chamber 30^f in casing 30. The construction of this valve is such that when the handle 80^c is in one position, communication from steam pipe 81 is shut off, and when said handle is in another position steam from pipe 81 will be supplied through both pipes 80^d and 80^e, the former serving as a supply for the engine 40, and the latter supplying the steam to chamber 30^f. An exhaust pipe 83 leads from the engine to and communicates with the chamber 30^f, in which is delivered the 120 exhaust from the engine 40. 125 130

When the entire mechanism is in operation, and steam is being supplied to engine 40 to operate the same, the screw conveyer 18 will operate to secure and convey coal 5 from the coal tender 16, discharging the same into the hopper 19^a. The pivotal mounting of the conveyer permits the same to follow the pile of coal downwardly as the same is decreased, or, when in the position 10 indicated in dotted lines in Fig. 1, will also convey coal to the hopper 19^a, and should the coal around the end of the conveyer 18 become exhausted, it is merely necessary to shovel or scrape more therearound, necessitating 15 but little labor and trouble. From the hopper 19^a the coal or like fuel is conveyed by conveyer 19 on through tube 21, from whence it drops into tube portion 22^a of closure 22, and from thence into and 20 through the nozzle 23. This nozzle may be oscillated vertically or horizontally, or both, by means of the gear and shaft mechanisms fully described above, and coal will be distributed to and through the entire fire-box. 25 To insure that coal will be thoroughly distributed to the near corners as well as to the body of the fire-box, I provide a deflecting member 90, see Figs. 1 and 3. This deflecting member is provided with the curved 30 surfaces 90^a adjacent the nozzle 23, so constructed and arranged as to deflect coal to the adjacent corners of the fire-box, as will be apparent. This deflector is subjected to intense heat, and consequently replacement 35 of the same becomes necessary from time to time. I, therefore, preferably construct it with a T-shaped groove or aperture 90^b in the rear portion thereof, the same fitting on and being supported by the T-shaped 40 bracket 90^c carried by the fire-box wall.

As has been explained above, variation in the amplitude of the oscillations of nozzle 23 may be provided by means of the adjusting mechanisms, and it will be obvious that 45 I may adjust the block 51 so that no horizontal oscillation of the nozzle will take place, or I may adjust the block 59 so that no vertical oscillation thereof will take place. Both of these blocks may be adjusted 50 so that no movement of the nozzle will take place at all. The construction of the arm 24, and its operative connection to nozzle 23 is such as not to interfere with the movement of the nozzle, and similarly the attachment 55 of shaft 26 to nozzle 23 is such as not to interfere with the vertical oscillation thereof. A shield or apron 23^c of nozzle tip 23^b serves to protect, to a certain extent, the link 24 and strip 23^b from the action of the heat 60 of the fire.

To assist in the distribution of the coal or like fuel, I have provided steam ducts and passages, and it will be apparent that when the entire system is in operation a direct 65 supply of steam through pipe 80^e will be

admitted to chamber 30^f, from whence it will flow through the apertures 27^d in rod 27 being admitted therethrough through the cross groove 27^e. From these apertures it will flow out through across grooves 27^b 70 through the passage 22^r to the passages 22^s, from whence it discharges axially through the nozzle 23, assisting in the discharge of the coal or other fuel therethrough and at the same time enhancing the draft of the 75 fire. The exhaust steam from the engine will flow through pipe 83 to chamber 30^b, and thence it will flow down through the central aperture 27^a of rod 27 through aperture 27^e and out through passage 22^v in arm 80 22^p up through short passage 22^w into the bend in passage 22^p of the closure 22, so that if coal becomes lodged therein, or is delayed in its progress through the passage 22^b, this exhaust steam will serve to dislodge and 85 hasten its progress. Also, should added coal be introduced through opening 22ⁿ, steam through passages 22^w will assist in delivering this to the nozzle. The flow of the steam through passages 22^s may be accurately regulated by the valves 22^u, as will be apparent. 90

The levers 60 and 61, shafts 25, 56, and 45 and bevel gears carried by said shafts, as well as by shaft 26, are all constructed and arranged, as will be apparent, to swing with 95 closure or door 22 about its hinged mounting, so that the installation of my mechanism does not interfere with the use of the locomotive fire-box, and the like, if it is desired to use the same in the ordinary manner, as becomes necessary under certain conditions. It is sometimes desirable to dispense with the running of engine 40, or it becomes sometimes necessary to start the mechanism from rest position, and for this 100 purpose I have provided the lever 70 and ratchet 41, through the medium of which, as will be apparent, shaft 40^c may be operated, to operate the balance of the mechanism. 105

When using my invention it will sometimes be found that a particular spot of the fire in the fire-box requires coal or like fuel, owing to the presence of a "hole" in the fire, and in this event I may throw the mechanical nozzle-oscillating means out of operation, as explained above, and move the nozzle by levers 61 and 70 to a position wherein it will concentrate its delivery of fuel to the spot in the fire where most 110 needed. Similarly, I may discontinue the use of either the horizontal or the vertical nozzle-operating means, using only the other of said means under certain conditions. 115

Another advantage of my construction 120 and mechanism is that the same may be readily applied to locomotives or similar structures now in use without the necessity of expensive and laborious alterations; and all of the mechanism being on the exterior of 125 130

the boiler or furnace and above the floor, it is apparent that access to all parts of the same may be easily had for the purpose of inspection, repairs, or the like.

5 It will be understood that my device, as shown in the accompanying drawings and described above, is susceptible of many modifications and changes, and I do not wish to be restricted to the form shown and 10 described beyond the scope of the appended claims.

I claim:

1. In combination with a locomotive having a fire box provided with a door, coal 15 conveying means, coal distributing means comprising a nozzle member movably mounted to distribute coal in said fire box, said nozzle member being associated with said fire box door to move with the same 20 when said door is opened and closed, and an auxiliary door controlling admission to said nozzle member.

2. In combination with a locomotive having a fire box and an opening leading thereto, fuel distributing means mounted in said 25 opening and comprising a casing member and a distributing nozzle, said nozzle being movably mounted and partially surrounded by said casing, said casing being provided 30 with a passage therethrough, and a flanged portion adjacent one end of said passage, said flanged portion projecting into a passage through said nozzle.

3. In combination with a locomotive having a fire box and an opening leading thereto, fuel distributing means mounted in said 35 opening and comprising a casing member and a distributing nozzle, said nozzle being movably mounted and partially surrounded by said casing, said casing being provided 40 with a passage therethrough, a flanged portion adjacent one end of said passage, said flanged portion projecting into a passage through said nozzle, and a rotatable 45 shaft carried by said casing and engaging said nozzle.

4. In combination with a locomotive having a fire box and an opening leading thereto, fuel distributing means mounted in said 50 opening and comprising a casing member and a distributing nozzle, said nozzle being movably mounted and partially surrounded by said casing, said casing being provided 55 with a passage therethrough, a flanged portion adjacent one end of said passage, said flanged portion projecting into a passage through said nozzle, and an oscillatable arm mounted in said casing and operatively connected to said nozzle.

60 5. In combination with a locomotive having a fire box and an opening thereto, a distributing member, a casing member forming a closure for said opening and distributing member, and means to swing said distributing member, said casing member be-

ing hinged to said locomotive to swing to or from closed position with respect to said fire box opening, said distributing swinging member being arranged to permit such movement of said casing.

70

6. In combination with a locomotive having a fire box with an opening leading thereto, a distributing nozzle member adapted to deliver coal to said fire box through said opening, a prime mover, a shaft adapted 75 to be rotated by said prime mover, means actuated by said shaft to vertically oscillate said distributing nozzle, means also actuated by said shaft to horizontally oscillate said nozzle, and means to throw into or out of 80 operation said vertically oscillating means, said horizontally oscillating means being operable alone when said vertically oscillating means is thrown out of operation.

7. In combination with a locomotive having a fire box with an opening leading thereto, a distributing nozzle member adapted to deliver coal to said fire box through said opening, a prime mover, a shaft adapted to be rotated by said prime mover, means actuated by said shaft to vertically oscillate said distributing nozzle, means also actuated by said shaft to horizontally oscillate said nozzle, and means to throw into or out of 90 operation said horizontally oscillating means, said 95 vertically oscillating means being operable alone when said horizontally oscillating means is thrown out of operation.

5

8. In combination with a locomotive having a fire box with an opening leading thereto, a distributing nozzle member adapted to deliver coal to said fire box through said opening, a prime mover, a shaft adapted to be rotated by said prime mover, means actuated by said shaft to vertically oscillate said distributing nozzle, means also actuated by said shaft to horizontally oscillate said nozzle, and means to throw into or out of 100 operation either or both of said oscillating means.

10

9. In combination with a locomotive having a fire box and an opening leading thereto, a distributing member arranged to feed coal through said opening, means to vertically oscillate said member, said means comprising a strip carried by said distributing member, an arm having a slot, said arm being carried by a rotatable shaft and a hand lever attached to said shaft, means to mechanically actuate said shaft, said means comprising a lever, means to throw said lever into or out of operable connection with said shaft, and means to oscillate said last named lever.

115

10. In combination with a locomotive having a fire box and an opening leading thereto, a distributing member arranged to feed coal through said opening, means to vertically oscillate said nozzle, said means comprising a strip carried by said distributing 120

125

130

- member, an arm having a slot, said arm being carried by a rotatable shaft and a hand lever attached to said shaft, means to mechanically actuate said shaft, said means comprising a lever, means to throw said lever into or out of operable connection with said shaft, said lever being slotted, a rotatable shaft angularly disposed with respect to said lever, a stud carried by said shaft, said stud being mounted in said slot in said lever, and means to move said stud to an eccentric position with respect to said shaft whereby rotation of the latter will oscillate said lever.
11. In a device of the class described, a main actuating shaft adapted to be rotated by a suitable source of power, a distributing member, means to horizontally swing said distributing member, said means comprising a rotatable shaft attached thereto, a block carried by said shaft, said block being slotted, a second shaft, a stud carried by said shaft and fitting in said slot and said block, and means to vary the eccentricity of said stud relative to said second shaft, said shafts and stud being arranged so that rotation of said second shaft will operate to oscillate said distributor shaft, said second shaft being operatively attached to said actuating shaft whereby rotation of the latter will operate to rotate the former.
12. The combination with a locomotive having a fire box and an opening leading thereto, a closure for said opening, a distributing member carried by said closure, and means to hingedly support said closure, said closure being provided with an arm, said arm being attached to a rotatable sleeve, said sleeve being bored, said arm being provided with a passage in communication with said bore and also with said distributing mem-
- ber, said arm and sleeve being further provided with second passages also in communication with said distributing member.
13. In a device of the class described, the combination with a steam supply, a closure, and a distributing member carried by said closure, said closure being hingedly mounted and provided with an arm, said arm being attached to a sleeve, said sleeve being provided with a main bore and said arm with a passage in communication with said bore, said bore being in communication with said steam supply and said passage with said distributing member whereby steam may be supplied to the latter, said arm being provided with a second passage, said sleeve being provided with a second bore, said second named bore and passage being also in communication with said steam supply and adapted to supply steam therefrom to said distributing member.
14. In a device of the class described, the combination with a steam supply, a closure, said closure being provided with a fuel supply passage therein, a distributing member carried by said closure and in communication with said passage, the latter being formed with a bend therein, means to supply steam to said passage and said closure adjacent the bend therein, and additional means to supply steam to said passage in approximate alignment with said distributing member.
- In testimony whereof, I have subscribed my name.

EDWARD PIERCE.
